UNITED STATES PATENT OFFICE.

JOSEPH A. LA RUE, OF PALESTINE, TEXAS.

LIQUID-DISPENSING APPARATUS.

Application filed December 7, 1926. Serial No. 153,098.

The present invention relates to a liquid dispensing apparatus and has for its principal object to provide a structure whereby liquid may be dispensed from the apparatus 5 upon the depositing of a coin.

Another important object of the invention lies in the provision of a coin controlled dispensing apparatus which will dispense a predetermined amount of fluid upon the 10 insertion of a coin therein.

A still further very important object of the invention lies in the provision of a coin controlled mechanism which includes an escapement mechanism, operating control 15 rods for the dispensing device, said escapement mechanism being set into operation by a trip releasable through the insertion of a coin into the apparatus.

A still further very important object of 20 the invention lies in the provision of an apparatus of this nature which is comparatively simple in its construction, inexpensive to manufacture, not likely to easily become out of order, thoroughly efficient and 25 reliable in its operation, and otherwise well adapted to the purpose for which it is designed.

With the above and numerous other objects in view as will appear as the description 30 proceeds, the invention resides in certain novel features of construction, and in the combination and arrangement of parts as will be hereinafter more fully described and claimed.

35 In the drawing:

Figure 1 is a front elevation of the apparatus embodying the features of my invention,

Fig. 2 is a sectional view taken there- 40 through substantially on the line 2—2 of Fig. 1,

Fig. 3 is a transverse section taken through the apparatus,

Fig. 4 is an enlarged detail sectional ele- 45 vation showing the releasable holding means for the control disk of the spring operated escapement mechanism,

Fig. 5 is a detail perspective view of a portion of the trip.

50 Referring to the drawing in detail, it will be seen that the numeral 5 denotes the casing which has a lid 6 held thereon by a suitable lock 7 or in any other preferred manner. A partition 8 divides the casing 5 up into a relatively large compartment A and a relatively small compartment B. A meas-

uring container 8' is located in the front bottom portion of the compartment A and has a pipe 9 leading rearwardly therefrom and at its rear end bent upwardly into a 60 funnel valve seat member 10. A rod 11 has a ball valve 12 on the lower extremity thereof which is adapted to seat into the member 10 for cutting off the flow through the pipe 9. A lever 14 is pivoted intermediate 65 its ends as at 15 on the upper edge of the partition 8 and the longer arm thereof extends into the compartment A while the shorter arm thereof extends into the compartment B. The extremity of the long arm 70 of the lever 14 is pivotally engaged with the rod 11 as at 16. A rod 17 is pivotally engaged at 18 with the extremity of the short arm of the lever 14 and extends downwardly into the compartment B where it is 75 pivotally engaged with one end of a rocker 19 pivoted intermediate its ends at 20. A rod 21 has a lost motion connection 22 with the other extremity of the rocker 19 and extends upwardly being pivotally engaged 80 as at 23 with a rod 24 having a weight 25 adjustably mounted thereon. The rod 24 extends radially from a shaft 26 which is journaled in the frame F. A second rod 27 extends radially from the shaft at an angle 85 to the rod 24, preferably an acute angle, and is offset to one side thereof and terminates in a lateral extension 29. A coin engaging plate 30 projects from the shaft 26 in a direction opposite to the rod 24 and is located 90 in the path of the coin dropped through the coin chute 31 in the top or lid 6 at the lock end thereof. An escapement mechanism E of any preferred construction is mounted in the frame F being operated by 95 a windable spring S. This escapement mechanism shown includes a plurality of meshing reducing gears having a wind-resistance element W in gear therewith. Such escapement mechanisms are well known in 100 the art and need no detailed description here. A disk 33 is operated by the escapement mechanism E and this disk as is shown to advantage in Figure 4 is of an oblong rounded construction having notches 105 35 at opposite ends of its shorter axis. The periphery of the disk enters notches abruptly as at 35 to one side and gradually as at 36 to the other side. The extension 29 is adapted to ride on the periphery as shown 110 in Figure 4.

The spring F is maintained in a wound

condition by a suitable key 37. A spigot 38 leads from the measuring container 8'. When the proper coin is dropped into the coin chute 31 it impinges on the coin engaging plate 30 and if of the proper denomination will overcome the balance of the adjustable weight 25 so as to rock the shaft 26 causing the lifting of the rod 21 to take up the lost play connection 22. The weight 10 of the coin will not be sufficient to rock the rocker 19 and the lever 14 to raise the valve 12 but will be sufficient to raise the extension 29 above the abrupt entrance 35 so as to ride on the sort of cam surface which is adjacent 15 thereto and thus the spring operating the escapement mechanism will cause the turning of the disk 33 in the direction of the arrow in Figures 2 and 4 so that the rod 27 will further rock the shaft 26 and swing 20 upwardly on the rod 24 so as to pull upwardly on the rod 21 and rock the rocker 19 pulling downwardly on the rod 17 and rocking the lever 14 to pull upwardly on the rod 11 to lift the valve 12. When the valve 25 12 is open it will be seen that the liquid in the compartment A will flow into the container 8' through the pipe 9 and the escapement mechanism will take sufficient time to turn the disk half a revolution so as to fill 30 this container 8'. When the disk has rotated a half revolution it will be seen that the parts will automatically swing back into their original position because of the weight 25 and the weight of the valve 12, rod 11 and the longer arm of the lever 14.

It is thought that the construction, operation, and advantages of this invention will now be clearly understood by those skilled in this art without a more detailed description thereof. The present embodiment of the invention has been disclosed in detail merely by way of example since in actual practice it attains the features of advantage enumerated as desirable in the statement of 40 the invention and the above description. It will be apparent that numerous changes in the details of construction and in the combination and arrangement of parts may be resorted to without departing from the

spirit or scope of the invention as herein- 50 after claimed or sacrificing any of its advantages.

Having thus described my invention what I claim as new is:

1. A coin controlled apparatus of the class 55 described including, in combination, an escapement mechanism including an oblong rounded disc having notches at opposite ends of the shorter diameter thereof, each notch having one abrupt approach and one gradual 60 approach, a shaft, a rod extending from the shaft, a coin trip plate extending from the shaft, a second rod extending from the shaft having an extremity arranged to ride on the periphery of the disc, a third rod pivotally 65 connected to the first rod, a valve, and a lever having means to operate the valve and having a lost motion connection with the third rod, whereby the deposit of a coin upon the trip plate will release the escapement 70 mechanism without operating the valve, said valve being operated by the rotation of the oblong disc engaging the extension of the second rod.

2. A coin controlled apparatus of the class 75 described including, in combination, an escapement mechanism including an oblong rounded disc having notches at opposite ends of the shorter diameter thereof, each notch having one abrupt approach and one gradual 80 approach, a shaft, a rod extending from the shaft, a coin trip plate extending from the shaft, a second rod extending from the shaft having an extremity arranged to ride on the periphery of the disc, a third rod pivotally 85 connected to the first rod, a valve, and a lever having means to operate the valve and having a lost motion connection with the third rod, whereby the deposit of a coin upon the trip plate will release the escapement 90 mechanism without operating the valve, said valve being operated by the rotation of the oblong disc engaging the extension of the second rod, and a weight ad- 95 justably mounted on the first rod.

In testimony whereof I affix my signature.

JOSEPH A. LA RUE.
